UNITED STATES PATENT OFFICE.

GARRISON W. DERRYBERRY, OF SPIRO, OKLAHOMA.

LIGHT ATTACHMENT FOR GUNS.

1,189,670.

Specification of Letters Patent.

Patented July 4, 1916.

Application filed May 26, 1914. Serial No. 841,075.

To all whom it may concern:

Be it known that I, GARRISON W. DERRYBERRY, a citizen of the United States, residing at Spiro, Le Flore county, and State of Oklahoma, have invented and discovered certain new and useful Improvements in Light Attachments for Guns, of which the following is a specification.

The object of my invention is to provide a light attachment for guns which is adapted for use either when attached to the gun for sighting objects in the dark or dusk, or for reconnoitering purposes, or for use around the camp, either attached to or detached 15 from the gun, all as will be hereinafter more fully described and claimed.

Figure 1 is a side elevation of a gun barrel showing my attachment applied thereto, as when in use thereon, Fig. 2 a top or plan view of the same, Fig. 3 a detail view showing the means for adjusting the telescopic sighting tube, and Fig. 4 a detail view showing the lamp detached.

In said drawings the portions marked A 25 represent the gun barrel, B the lamp casing, and C the sighting tube.

The gun barrel A is, or may be, the barrel of any gun such as is in common use.

The lamp casing is preferably of metal 30 and cylindrical in form, the lower end being provided with a hinged bottom b on which a lamp 10 is supported. The bottom b is preferably mounted on a hinge 11 and may be held closed by a catch 12 of any appropriate form, such as shown. The lamp 10 is preferably a carbid lamp, but may be an oil, or any other type of lamp desired and found suitable. The term "light", as used in the 35 claims, will be understood to mean any such means for producing the light required. It is arranged to provide a light directly in front of a strong reflector 22 and in line with the center of the sighting tube C, and the center of said tube is arranged in line 40 with the center of the gun barrel and parallel therewith. Said light is mounted to turn on a pivot so as to be brought to different positions and the lamp casing B is provided with a side lens 14 in the same 45 plane with and to one side of the sighting tube C. Said sighting tube C is adapted to screw into a screw-threaded neck around an opening in the side of casing B alongside and adjacent to the lens 14. Said sighting tube C is preferably formed with a telescopic section C¹ which slides within tube C 50 55

and may be adjusted longitudinally thereof by means of a pinion 15 on a cross shaft 16 which engages with rack teeth 17 on the under surface of said section C¹.

The lamp 10 is formed with a central depression in its bottom which is adapted to fit over a boss or projection 18, centrally located on the upper side of the hinged bottom b of the lamp casing B. A handle 19 projects through a segmental slot in one side of said casing B by which said lamp 10 may be turned or pivoted on said projection. By this means the lamp may be turned at will to throw the light through the sighting tube 70 C, or through the lens 14.

The tube C is supported on the gun barrel by a series of clamping brackets 20 which surround the gun barrel and the sighting tube and are clamped in position by clamping screws 21. By this means the sighting tube may be readily removed and attached to any gun barrel as desired.

In use the parts being in the position shown in Figs. 1 and 2, the light is projected through the lens 14 to one side of the gun barrel and at an angle therewith. The gun being placed in appropriate position in the camp the lamp is rendered available for use as a reading lamp or for other 85 purposes around the camp, as for reconnoitering, etc. By turning the handle 19 to the right the lamp 10 is turned to bring the light directly opposite the center of the sighting tube C. The reflector 22, of appropriate power, is located immediately behind the light and turns with the lamp, so that the light being brought in line with the end of tube C is projected by said reflector through the tube and in line with the gun 90 barrel beyond its outer end. By this means any object at a distance can be located and game can be not only located, but shot after dark.

By unscrewing the sighting tube C from 100 the neck surrounding the screw-threaded aperture provided therefor, the lamp is entirely freed from the gun and may be used for any purpose desired. The outer end of section C¹ of tube C is provided with a 105 lens 23 which may be unscrewed from said end and screwed into the opening in the side of the casing B, adapted for the sighting tube, or any other appropriate cover, or cap, may be fixed to said opening, as will be 110 readily understood.

Having thus fully described my said in-

vention, what I claim as new and desire to secure by Letters Patent is:

1. A lamp attachment for guns comprising a lamp casing having relatively angular openings, a sighting tube detachably connected with one of said openings, a lamp mounted in said casing, and means associated with said lamp for directing the light rays therefrom through either of said openings and preventing their passage through the other opening, substantially as set forth.
2. A light attachment for guns comprising a sighting tube adapted to be secured to the gun barrel, a casing having a perforation into which the end of said sighting tube may be inserted, said casing being provided with another opening at an angle from the opening which receives the sighting tube, a lamp within said casing positioned to bring the light in line with said openings, and means for turning said lamp to throw the light opposite either opening desired, substantially as set forth.
3. A light attachment for guns comprising a lamp casing formed with openings at an angle with each other, a sighting tube detachably secured in one of said openings, a lens covering the other of said openings, a lamp within said casing mounted to be turned, and means for turning said lamp to bring the light opposite either of said openings, substantially as set forth.
4. An attachment for guns comprising a detachable sighting tube adapted to be secured to the side of the gun barrel, a lamp casing detachably secured to the inner end

of said sighting tube, and formed with an opening to one side of the attachment of said sighting tube, and a shiftable light within said lamp casing adapted to be shifted to throw the light through the sighting tube or through the other opening, substantially as set forth.

5. An attachment for guns comprising a sighting tube adapted to be attached to the gun barrel, a lamp casing detachably secured to said sighting tube and having a side opening, a light in said lamp casing, a reflector positioned behind said light, and means for turning said light and reflector to throw the light through said sighting tube or said side opening, substantially as set forth.

6. A light attachment for guns comprising a casing, a sighting tube secured to said casing, means for attaching said sighting tube to the gun barrel, said lamp casing being formed with an opening in the same plane with the sighting tube but to one side thereof, a lamp within said casing, and means for turning said lamp to bring the light opposite the sighting tube or the other opening as desired, substantially as set forth.

In witness whereof, I have hereunto set my hand and seal at Washington, District of Columbia, this ninth day of May, A. D. nineteen hundred and fourteen.

GARRISON W. BERRYBERRY. [L. S.]
